HAIR WAVING APPARATUS

Eli Ray Boals, Pasadena, Calif., assignor to Harry F. Thompson, Pasadena, Calif.

Application July 31, 1933, Serial No. 682,902

4 Claims. (Cl. 132—36.1)

This invention relates to improvements in hair waving apparatus and more particularly to protective clamps therefor.

The use of heat, moisture and electricity in the conventional "permanent" waving of human hair involves three serious dangers to the person being operated upon; to wit, electrocution, dry burning and/or scalding the scalp.

Among the objects of this invention is to eliminate the above dangers.

Another object is to interpose dielectric heat nonconducting clamps between the heating element and the scalp of the person.

Another object is to imbed all metallic fixtures in the dielectric clamp body to insulate the scalp from the electrical apparatus.

Another object is to so construct and arrange the meeting jaws of the clamp that the lock of hair held therein will be shaped and disposed to arrest capillary attraction of moisture and the flow of hot vapors at the clamp.

Another object is to provide moisture cups in the clamps to retain any condensation or hot liquids incidental to the waving operation.

A further object is to so combine, arrange and unify the clamp assembly that its application and functioning will save the operators' time and render the operation more efficient.

Other objects and advantages will appear as the description progresses.

"Permanent" hair waving is divided into two major classes: the "spiral" and the "croquignole". The former is superior in results and preferred by the majority of users, but until the present invention the dangers above set forth and other incidental discomforts have minimized the demand. The spiral also has previously required superior skill because of the inefficiency of the apparatus, especially the clamps.

The present invention, with slight modifications, is equally applicable to both types and combines the efficiency and economies of the croquignole with the superior results of the spiral type.

In this specification and the accompanying drawing the invention is disclosed in its preferred form. It is to be understood, however, that it is not limited to this form because it may be embodied in other forms within the spirit of the invention as defined in the claims following.

In the one sheet of drawings:

Fig. 1 is an enlarged plan view from above of a clamp constructed in accordance with this invention. Some of the parts are shown in fragmentary horizontal section.

Fig. 2 is a side elevation of the same partially broken away in vertical section to show the embedded hinge structure.

Fig. 3 is a cross section of the same taken on the line III—III, Fig. 2.

Fig. 4 is a reverse view of Fig. 2 showing the structure of the embedded latch mechanism.

Fig. 5 is a reverse view of Fig. 1 showing the bottom of the clamp with the felt insert.

Fig. 6 is a side assembly view showing the application of the present clamp in connection with the heater for a spiral wave.

Fig. 7 is a plan view from above of a croquignole type clamp modified in accordance with this invention.

Fig. 8 is a cross section of the same on the line VIII—VIII, Fig. 7.

In detail the construction illustrated in the drawing, referring to Fig. 1, comprises the jaws 1 and 2 hinged together for relative movement by the embedded strap 3 fixed in the jaw 2 by the pin 4. The opposed jaw 1 pivots on the pin 5.

These jaws are drawn together by a latch consisting of the link 6 embedded in the opposed jaws and pivotal on the pin 7 fixed in the jaw 2. The latch lever 8 has a bifurcated head 9 pivotal on the pin 10 fixed in the outer end of the link. In the operative position both the hinge and the latch mechanisms are embedded in the jaws 1 and 2 within the peripheral margins thereof.

The jaw 1 has the latch lugs 11—11 engaged by the cams 12—12 on the head 9. When the latch is engaged, these cams and lugs act as eccentrics to draw the meeting edges of the jaws 1 and 2 together.

The opposed edges of the jaws are channeled to receive the beads 13 and 14 formed on the resilient rubber packing strips 15 and 16, respectively, which thus form the meeting edges of the jaws 1 and 2. The packing strips seal the meeting line against the passage of liquid and vapors from the heating element 28, see Fig. 6, which will hereinafter be more fully described. The overhanging lips 17 and 18 divert such liquid into the depressions or cups 1' and 2' formed in the tops of the jaws respectively.

The ends of the packing strips are shaped to abut the shoulders 19 and 20 on their respective jaws to prevent lineal travel of the strips when they are compressed by the latch 6—8.

The jaws are provided with the depending peripheral flanges 21 and 22 surrounding the lower plane of the combined jaws, see Fig. 5. This plane is covered by the protective pad 23 prefer-

ably of felt and detachably secured in place by the common pins 24—24 passing through perforations in the flanges and penetrating the pad 23. These perforations are countersunk to receive the pin heads to prevent them entangling in the hair, yet be easily accessible for withdrawal of the pad for sterilization.

This pad is slit as at 23' to register with the meeting line 25 of the packing strips 15 and 16. It is preferable not to completely bisect the pad leaving the "hinge" at 26 to maintain the integral strength of the pad as much as may be when the slit 23' opens with the jaws 1 and 2.

The same general structure of the clamp is maintained in the "croquignole" type shown in Fig. 7. Corresponding parts bear the common reference numbers with *x* added. In this instance the jaws 1*x* and 2*x* are straight bars instead of semicircular as in the spiral type. They are hinged together at 3*x* in the conventional manner and drawn together by the latch 6*x*—8*x*.

The soft rubber strips 15*x* and 16*x* are interposed between the jaws at the meeting line 25*x*. The felt bars 23*x* and 23' *x* are fixed to their respective jaws by the pins 24*x* passing through the flanges 21*x* and 22*x*. The lock of hair to be waved is clamped and wound upon a ratchet rod (not shown) in the conventional croquignole manner.

This invention operates substantially as follows: The hair of the head of the wearer is divided into separate locks each of which is clamped between the jaws 1 and 2 of the clamps as near the scalp as practicable. The yielding strips 15 and 16 surround the lock of hair to prevent steam and liquid penetrating to the scalp. Heretofore there has been a certain amount of capillary seepage through clamps having round or elliptical opening therethrough because the rubber jaws cannot be depended upon to seal the gaps on opposite sides of the lock of hair on the meeting line of the clamp jaws.

In the present invention this seepage is overcome by the peculiar shape of the jaws immediately surrounding the lock of hair, see Figs. 1 and 2. The intermediate portion of the meeting line is deflected as from A to B in Figs. 1 and 5. It will be noted that the arcuate line bisects the straight meeting line C of the jaws. This substantially right angle meeting at A and B effectively seals the meeting strips 15 and 16 on opposite sides of the clamped lock of hair. Even though the lock assumes a substantially crescent shape in cross section between the points A—B, the converging lines at these points will insure a perfect seating of the packing strips one against the other since they are not subject to wedging action of the thickness of the hair forming the lock.

The cam latch at 11—12 is capable of distorting the jaws if an excessive amount of hair is interposed causing a dangerous leakage between them. This danger is negligible when the hair clamping areas are concentrated at a point lateral to the normal meeting line C, as in Figs. 1, 5 and 7.

This intermediate lateral gap in the jaws 1 and 1*x* greatly facilitates the concentrated even distribution of the strands forming the lock of hair H, prior to the closing of the clamp.

In the spiral type, Fig. 1, the arcuate arrangement provides a free center portion for the disposition of the end 25 of the curling rod, see Fig. 6. Above the clamp the hair waving technique is conventional. The string 26 is looped and tied

and the loop passed under the yielding clip 27 fixed to the top of the clamp. The string is then passed through the slot in the end of the rod and then around the lock of hair H and back through the slot. The hair is then spiraled around the rod and tied at the outer end. The winding and tying technique will vary with the type of rod used and the nature of the hair wave desired.

The rod with the hair tied thereto is then enclosed in the usual saturated pad and enclosing paper 28' and inserted in the heating element 28 in the usual manner.

During the steaming period the curling solution flows from the wet pad into the hair and any excess and condensation runs down the rod and collects on top of the clamp. In the present instance, it drains into the depressions 1' and 2'. In the old types of clamps this hot drainage would seep between the jaws or run along the meeting line of the jaws and drip off the ends directly onto the scalp causing discomfort when it did not develop serious scalds.

A further advantage of the depressions 1', 2' and 1' *x* and 2' *x* is the high thermal insulating efficiency of the dead air impounded in the depressions between the clamp and the heater 28 to protect the scalp from transmitted heat.

As a further protection against heat and moisture, the removable absorbent felt pad 23 is interposed between the clamp and the scalp. In addition to its attaching function, the flanges 21 and 21*x* compress the felt pads to close the slit 23' in Fig. 5 and 23' *x* in Fig. 8 to insure capillary attraction between the protective pads and the hair soaked with the curling solution to prevent the liquid reaching the scalp. These solutions are often highly alkaline and irritating to the scalp when heated.

Attention is directed to the fact that no electro conductive parts, such as the hinge and latch structures, extend through the clamp between the heater 28 and the pad 23. This is an important precaution to avoid electric shocks to a moist scalp.

There are many synthetic compositions now available for molding the jaw parts in the suggested forms shown. These are largely composed of formaldehyde-phenol binders for asbestos and other inert constituents for dielectrics of low thermal conductivity forming compositions popularly known as bakelite. I do not wish to be understood as limiting this invention thereto since the jaws of the clamp could be cast in suitable metals or built up of die stampings as commonly used in this art without sacrificing the functional advantage set forth.

Having thus described this invention what is claimed and desired to secure by Letters Patent is:

1. A clamp for the purpose described including hinged jaws having resilient meeting edges, the meeting line of said edges being arcuately deflected intermediate its length; and a latch adapted to compress said edges together.

2. A clamp for the purpose described including jaws of dielectric heat insulating material having resilient meeting edges; a hinge projecting from one of said jaws and completely embedded in the opposed jaw; and a latch embedded in said jaws within the margins thereof and adapted to compress said edges together.

3. A clamp for the purpose described including a pair of hinged jaws having flanged peripheries and resilient meeting edges; a latch adapted to compress said edges together; a protective pad

within said peripheral flanges and pins engaging said flanges and pad.

4. A clamp for the purpose described including jaws of dielectric, heat insulating material having depressions in their upper planes; compressible packing strips interposed between the meeting edges of said jaws and having flanged edges

overlying the edges of said jaws; a protective pad fixed to the under side of said jaws and having a slit registering with the meeting line of said packing strips; and a latch adapted to compress said packing strips and the meeting edges of said slit together respectively. 5
